US0D1053184S

(12) **United States Design Patent** (10) **Patent No.:** **US D1,053,184 S**
(45) **Date of Patent:** **** Dec. 3, 2024**

(54) **INFORMATION HANDLING SYSTEM**

(71) Applicant: **Dell Products L.P.**, Round Rock, TX (US)

(72) Inventors: **Yongook Guack**, Leander, TX (US); **Erik Summa**, Austin, TX (US); **James Tsai**, Mercer Island, WA (US); **Potter Tai**, New Taipei (TW); **Hann Wu**, Taipei (TW)

(73) Assignee: **Dell Products L.P.**, Round Rock, TX (US)

(**) Term: **15 Years**

(21) Appl. No.: **29/883,127**

(22) Filed: **Jan. 24, 2023**

(51) LOC (14) Cl. **14-02**

(52) U.S. Cl.

USPC **D14/314; D14/349**

(58) **Field of Classification Search**

USPC ..... D14/140.2–140.3, 300–302, 308–309, D14/311–312, 314, 348–349, 352–359, D14/444–446; D13/103, 110, 112, 122, D13/158–160, 184; D21/324, 499, 515 CPC G11B 33/02; G11B 33/022; G11B 33/025; G06F 1/20

(57) **CLAIM**

The ornamental design for an information handling system as shown and described.

DESCRIPTION

FIG. 1 is a front left perspective view of the information handling system comprising the present invention;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof;

FIG. 8 is a front right perspective view thereof; and,

FIG. 9 front left lower perspective view thereof.

The portions of the information handling system shown in stippling illustrate areas of contrasting appearance. Broken lines shown in the drawings illustrate portions of the information handling system and form no part of the claimed design.

1 Claim, 9 Drawing Sheets
